DESIGN FOR A TROUSER-SKIRT

Violet Giovagnoni, New York, N. Y.

Application April 20, 1942, Serial No. 106,626

Term of patent 3½ years

To all whom it may concern:

Be it known that I, Violet Giovagnoni, a citizen of the United States, residing in New York city, in the county of New York and State of New York, have invented a new, original, and ornamental Design for a Trouser-Skirt, of which the following is a specification, reference being had to the accompanying drawings, forming part thereof.

Fig. 1 is a front view of a trouser-skirt showing my new design,

Fig. 2 is a rear view of the trouser-skirt shown in Fig. 1, and

I claim:

The ornamental design for a trouser-skirt, substantially as shown.

VIOLET GIOVAGNONI.
